REFRIGERATION

Robert R. Candor, Dayton, Ohio, assignor, by
mesne assignments, to General Motors Corporation,
a corporation of Delaware

Application September 29, 1932, Serial No. 635,389
Renewed April 16, 1937

18 Claims. (Cl. 62—4)

This invention relates to refrigeration, and more particularly to refrigerating systems of the character which operate continuously without stopping for temperature adjustments in an object being cooled. Such systems are stopped a relatively few times compared with the stopping operations of the usual intermittently operating refrigerating system which stops for temperature adjustments in the object being cooled. In the continuously operating systems or in those systems which are designed to operate substantially continuously and stop only for defrosting, repairs or the like, or when the atmospheric temperature drops below the normal range, the period of idleness is extremely long, so that the refrigerant pressure in the system will become substantially equalized throughout the system. Because of this, these systems need not, and generally are not, provided with special unloaders for the compressor, and therefore are likely to fail to restart if the attempt is made to restart them relatively soon after they have been stopped. It may occur in the operation of these systems that the line current, or source of electrical energy, may fail for a relatively short period of time, due to an electrical storm or the like, and it is desirable that the refrigerating system should restart automatically and safely after such a temporary failure of the line current.

It is among the objects of this invention to provide an improved control for the electric motor which drives the refrigerating system which is capable of automatically starting the motor when the current is turned on by the user, which is capable of restarting the system safely if the line current, or source of electrical energy should be turned off temporarily and then be turned on before the refrigerant pressure has equalized sufficiently to permit the motor to start. My control is particularly useful in that it insures a relatively long period of rest if the motor should fail to restart on the first attempt, and thus insures that the system has unloaded the compressor before a second attempt to restart.

Further objects and advantages of the present invention will be apparent from the following description, reference being had to the accompanying drawing, wherein a preferred form of the present invention is clearly shown.

In the drawing:

Fig. 1 is a diagrammatic representation of a system embodying the features of my invention; 55 and

Fig. 2 is a diagrammatic representation of a slightly modified system.

A refrigerating system embodying features of this invention is designed to operate continuously during the normal atmospheric temperature range in a dwelling without stopping for cabinet temperature adjustments and is of such a character and capacity, that it automatically maintains proper temperature conditions in the object to be cooled, notwithstanding such continuous operation. Such a system has been more fully described in the copending application, Serial No. 599,239, filed March 16, 1932, to which reference is hereby made for a further disclosure of such a system.

Briefly, such a system includes a compressor 10, a condenser 11, an evaporator 12. The compressor discharges the compressed refrigerant to the condenser 11 which in turn discharges liquefied refrigerant through the expansion device 13 to the evaporator 12 where the refrigerant is evaporated and returns through the line 14 to the compressor 10. The expansion device 13 may be of any suitable character, but preferably is of the elongated orifice type which maintains a fixed, and continuously open orifice, so calibrated as to length and cross-sectional area, that it maintains the evaporator 12 at the proper temperature to maintain the object being cooled at a substantially constant temperature notwithstanding variations in the surrounding atmosphere. In such a system, the elongated orifice in the expander 13 permits a continuous passage of refrigerant therethrough, and should the compressor 10 stop temporarily, this flow through the orifice continues and in a relatively short time equalizes the pressures throughout the refrigerating system, so that if the compressor should be restarted after such a short time, it starts with substantially no load.

Under ordinary conditions, such a system is stopped only for the purpose of defrosting the evaporator 12 and this defrosting operation is performed only once or twice a month and is not of the type of stopping operation which is intended to maintain temperature conditions in the object being cooled. On the contrary, such a stopping operation generally permits the object being cooled to warm above the desired temperature, but the operation is performed because of the large accumulation of frost on the evaporator and because of its undesirable inconvenience. After such a stopping operation and because of its long duration, the compressor starts under no load characteristics and hence

the compressor need not be provided with unloading mechanism, other than the expander 13 itself. The motor 15 for driving the compressor may be of the split phase type which is provided with a starting winding 16 and a running winding 17, and, as is usual with this type of motor the starting torque is small. Such a motor compressor unit is capable of starting only if the entire refrigeration system has been 5 come substantially equalized as to pressure throughout, or if the unit is provided with an automatic unloader for removing the pressure differential load during the starting period. In this particular system, no unloader need be used, 10 as it is possible to permit the system to equalize by a sufficiently long period of idleness during the infrequent stops which may be necessary.

A control is provided for this system which automatically and safely restarts the motor after 20 a temporary line failure, and this control includes means for insuring a relatively long rest period if the motor should fail to start after the first attempt after a line failure. This relatively long period of rest insures that the refrigerant pressures in the refrigerating system may equalize 25 and thus insure that the next restarting attempt will be made with a much easier pressure differential in the compressor. To this end, the windings of the motor are provided with a control 18 which maintains the starting winding energized 30 during a starting period and deenergizes the starting winding at the termination of the starting period. Another control 19 is provided which insures that a relatively long period of rest is 35 provided if the motor should fail to start on the first attempt after a line failure before a second restarting attempt is made.

The control 18 includes a solenoid 20 which is adapted to close the contact 21 by virtue of the 40 surge current flowing through the main winding 17 during the starting period, and which is of insufficient strength to hold the contact 21 closed after the motor has attained normal speed. The control 19 includes a thermostatic strip 22 which 45 may or may not be under the influence of the heat of the motor, and which is heated by the resistance 23 which is in series with the line or source of electrical energy 24 and the motor 15. The thermostatic strip 22 is adapted to open the contact 25 by a snap action against a magnetic 50 resistance 26 when the heater 23 has been overloaded by an abnormal flow of current for a predetermined period of time such as a period slightly longer than the normal starting period of 55 the motor 15. The strip 22 is provided with an engaging means, or hook, 27 adapted to engage the thermostatic strip 28 and be held in locked position therewith so long as the motor casing 29 is at a temperature near to normal running 60 temperature or at any warmer temperature. Thus, if after a temporary line failure, the control 18 should attempt to start the motor 15, and the motor 15 should fail to start, the resistance 23 will be warmed sufficiently to cause the hook 27 65 engaging means 27 to engage the thermostatic strip 28 and be held locked therein so long as the motor casing 29 is near the normal running temperature. The strip 28 will hold the engaging means 27, and therefore the contact 25 open, until 70 the motor casing 29 cools sufficiently for the strip 28 to assume its cooled position 30 indicated in dotted lines in Fig. 1. Therefore, if there should be a temporary line failure, and the current should return before the system has had an opportunity 75 to equalize as to refrigerant pressure

and consequently before the motor casing 29 has had an opportunity to cool, then upon failure of the motor 15 to start, the contact 25 would be opened and would be held open by the strip 28 during the relatively long period of time which it takes the motor 15 to cool, thus giving a sufficiently long period of time for the refrigerant pressure to equalize or to reduce the pressure differential a substantial amount.

If desired, a manual reset 31 may be provided 10 for manually releasing the engaging means 27 and permitting the contact 25 to close before the motor casing 29 has cooled, this manual reset 31 conveniently being in the form of a knob extending 15 from the switch casing (not shown) and being connected to the strip 28 so that it may be manually depressed to release the hook 27. The manual reset 31 is intended to be used by repairmen or the like when they do not wish to wait for the normal cooling period of the motor. 20

A manual control for stopping and starting the system by the user for defrosting or the like may be provided. Conveniently one of the contacts already provided may be used. Thus a stop 32 may be provided on the rod 33, which rod may be 25 slidably connected with the strip 22 in such a manner that the contact 25 may be opened without disturbing the strip 22. A snap acting, manually operated, lever construction 34 is provided to engage the hook 35 which forms an extension of the rod 33. Thus the user may operate the lever construction 34 to open the contact 25 without disturbing the strip 22, or may operate the lever construction to permit the contact 25 to be governed by the control 19. 30

In the modification shown in Fig. 2, a slightly different construction is used so that the electric circuit may be opened if the motor casing becomes overheated. Portions of the system which are designated by the same reference characters, with 40 the suffix "a" added, which are used in Fig. 1, may be of the same construction and function already described with respect to Fig. 1. The control 19, however, may be replaced by the control 40 shown in Fig. 2, which control includes the thermostatic strip 41 heated by the resistance 42 which is in series between the source of electrical energy 24a and the motor 15a. The strip 41 is adapted to open the contact 43 if the motor 15a should fail to start after a temporary line failure by reason 50 of the overheating of the resistance 42. The strip 41 is provided with engaging means 44 adapted to engage the hook 45 while the motor casing 29a is at normal temperature or warmer. The engaging means 44 shown in Fig. 2 is pivoted 55 at 44a to permit the same to pass over the hook 45, but the pivot permits the member 44 to pivot upwardly only and is urged against any pivoting movement below the horizontal position as will be well understood by those skilled in the art. The 60 hook 45 is adapted to be retracted upon the cooling of the casing 29a by reason of a thermostatic strip 46 mounted on the casing 29a which occupies the full line position at normal running temperatures, but occupies the hook retracting 65 position 47 shown in dotted lines when the casing 29a has cooled. A manual control 48 similar to the control 34 is adapted to engage the hook 49 in a manner similar to the engagement of the hook 35. 70

In addition, the modification shown in Fig. 2 is adapted to provide means for insuring that the system shall not operate when the motor casing 29a has become overheated. To this end the thermostatic strip 46 is adapted to engage the 75

5 sleeve 50 which opens the contact 51 when the motor casing 29a becomes overheated and causes the strip 46 to assume the dotted position 47' to the right of the full line position shown in Fig. 2.

10 A manual reset 52 may be provided conveniently on the hook 45 to permit a manual reset before the motor has cooled in a manner similar to the reset 31 described with respect to Fig. 1.

15 While the form of embodiment of the invention as herein disclosed, constitutes a preferred form, it is to be understood that other forms might be adopted, all coming within the scope of the claims which follow.

20 15 What is claimed is as follows:

25 1. A refrigerating system including a compressor, condenser and evaporator in a closed refrigerant circuit, an electric motor for driving said compressor, said motor having a starting winding and a running winding, a source of electrical energy, means for maintaining the flow of current from said source through said starting winding during a starting period and for stopping the flow of said current at the termination of said starting period, means for rendering said first named means reoperative after a temporary interruption in the supply of electrical energy, and means responsive to the normal operating temperature of a member of said refrigerating system for preventing the flow of current through said windings for a predetermined period of time if said temporary failure should prove to be of insufficient duration to unload said refrigerating system, and means for equalizing refrigerant pressures in said system during said predetermined period.

30 2. A refrigerating system including a compressor, condenser and evaporator in a closed refrigerant circuit, an electric motor for driving said compressor, said motor having a starting winding and a running winding, a source of electrical energy, means for maintaining the flow of current from said source through said starting winding during a starting period and for stopping the flow of said current at the termination of said period, means for rendering said first named means reoperative after a temporary interruption in the supply of electrical energy, and means responsive to the normal operating temperature of said motor for preventing the flow of current through said windings for a predetermined period of time if said temporary failure should prove to be of insufficient duration to unload said refrigerating system, and means for equalizing refrigerant pressures in said system during said predetermined period.

35 3. A refrigerating system of the type which runs continuously without stopping for cabinet temperature adjustments in normal household atmospheric temperatures and including a compressor, a condenser and an evaporator in a closed refrigerant circuit, an electric motor for driving said compressor, said motor having a starting winding and a running winding, a source of electrical energy, means for maintaining the flow of current from said source through said starting winding during a starting period and for stopping the flow of said current at the termination of said starting period, means for rendering said first named means reoperative after a temporary interruption in the supply of electrical energy, means responsive to the normal operating temperature of a member of said refrigerating system for preventing the flow of current through said windings for a predetermined period of time if said temporary failure should prove to be of insufficient duration to unload said refrigerating system, and means for equalizing refrigerant pressures in said system during said predetermined period.

40 4. A refrigerating system including a compressor, condenser and evaporator in a closed refrigerant circuit, an electric motor for driving said compressor, said motor having a starting winding and a running winding, a source of electrical energy, means for maintaining the flow of current from said source through said starting winding during a starting period and for stopping the flow of said current at the termination of said starting period, means for rendering said first named means reoperative after a temporary interruption in the supply of electrical energy, and means responsive to the normal operating temperature of said motor for preventing the flow of current through said windings for a predetermined period of time if said temporary failure should prove to be of insufficient duration to unload said refrigerating system, said period of time being longer than said starting period, and means for equalizing refrigerant pressures in said system during said predetermined period.

45 5. A refrigerating system including a compressor, condenser and evaporator in a closed refrigerant circuit, an electric motor for driving said compressor, a source of electrical energy, means for interrupting the supply of current to the motor upon excessive current passing thereto and for automatically re-initiating operation of the motor thereafter, means brought into operation upon actuation of the first named means after a temporary interruption in the supply of electrical energy for preventing the flow of current to said motor for a predetermined period of time if said temporary interruption should prove to be of insufficient duration to unload said refrigerating system, and means for equalizing refrigerant pressures in said system during said predetermined period.

50 6. A refrigerating system including a compressor, condenser and evaporator in a closed refrigerant circuit, an electric motor for driving said compressor, a source of electrical energy, means for interrupting the supply of current to the motor upon excessive current passing thereto and for automatically re-initiating operation of the motor thereafter, means brought into operation upon actuation of the first named means after a temporary interruption in the supply of electrical energy for preventing the flow of current to said motor for a predetermined period of time if said temporary interruption should prove to be of insufficient duration to unload said refrigerating system, and means for equalizing refrigerant pressures in said system during said predetermined period.

55 7. A refrigerating system including a compressor, condenser and evaporator in a closed refrigerant circuit, an electric motor for driving said compressor, a source of electrical energy, means for interrupting the supply of current to the motor upon excessive current passing thereto and for automatically re-initiating operation of the motor thereafter, means brought into operation upon actuation of the first named means after a temporary interruption in the supply of electrical energy for preventing the flow of current to said motor for a predetermined period of time if said temporary interruption should prove to be of insufficient duration to unload said refrigerating system, and a continuously open expansion device between said condenser and evaporator for equalizing refrigerant pressures in said system during said predetermined period.

60 8. A refrigerating system including a compressor, condenser and evaporator in a closed refrigerant circuit, an electric motor for driving said compressor, a source of electrical energy, means for interrupting the supply of current to the motor upon excessive current passing thereto and for automatically re-initiating operation of the motor thereafter, means brought into operation upon actuation of the first named means after a temporary interruption in the supply of electrical energy and responsive to the normal operating temperature of a member of said refrigerating system for preventing the flow of current through said windings for a predetermined period of time if said temporary failure should prove to be of insufficient duration to unload said refrigerating system, and means for equalizing refrigerant pressures in said system during said predetermined period.

current to said motor for a predetermined period of time if said temporary interruption should prove to be of insufficient duration to unload said refrigerating system, and means for equalizing refrigerant pressures in said system during said predetermined period.

8. A refrigerating system including a compressor, condenser and evaporator in a closed refrigerant circuit, an electric motor for driving said compressor, a source of electrical energy, means for interrupting the supply of current to the motor upon excessive current passing thereto and for automatically re-initiating operation of the motor thereafter, means brought into operation upon actuation of the first named means after a temporary interruption in the supply of electrical energy and responsive to the normal operating temperature of said motor for preventing the flow of current to said motor for a predetermined period of time if said temporary interruption should prove to be of insufficient duration to unload said refrigerating system, and means for equalizing refrigerant pressures in said system during said predetermined period.

9. A refrigerating system including a compressor, condenser and evaporator in a closed refrigerant circuit, an electric motor for driving said compressor, a hermetically sealed casing enclosing said motor and compressor, said compressor being constantly subjected to the pressure difference between the condenser and the evaporator, a source of electrical energy, means for interrupting the supply of current to the motor upon excessive current passing thereto and for automatically re-initiating operation of the motor thereafter, means brought into operation upon actuation of the first named means after a temporary interruption in the supply of electrical energy for preventing the flow of current to said motor for a predetermined period of time if said temporary interruption should prove to be of insufficient duration to unload said refrigerating system, and means for equalizing refrigerant pressures in said system during said predetermined period.

10. A refrigerating system including a compressor, condenser and evaporator in a closed refrigerant circuit, an electric motor for driving said compressor, a source of electrical energy, said compressor being constantly subjected to the pressure difference between the condenser and the evaporator, means for slowly equalizing refrigerant pressures upon the inlet and discharge sides of the compressor after the compressor stops, and means for preventing more than one attempt at starting the motor before the pressures have equalized sufficiently to permit the motor to start.

11. A refrigerating system including a compressor, condenser and evaporator in a closed refrigerant circuit, an electric motor for driving said compressor, a source of electrical energy, said system including means for slowly equalizing the refrigerant pressures in said system upon stopping of the compressor, and means for maintaining the motor deenergized for a period long enough for the pressures to equalize sufficiently for the motor to start after a single attempted start which is unsuccessful because of the pressure difference across the compressor being too great.

12. A refrigerating system including a compressor, condenser and evaporator in a closed re-

frigerant circuit, an electric motor for driving said compressor, said system being provided with means for equalizing refrigerant pressures upon opposite sides of the compressor when the compressor is idle, a current responsive overload control for said electric motor, and means for delaying the closing of the current responsive overload control to provide an idle period of the compressor sufficient to unload the compressor.

13. A refrigerating system including a compressor, condenser and evaporator in a closed refrigerant circuit, an electric motor for driving said compressor, said system being provided with means for equalizing refrigerant pressures upon opposite sides of the compressor when the compressor is idle, a current responsive overload control for said electric motor, and means responsive to the temperature of said electric motor for controlling the closing of said current responsive control.

14. A refrigerating system including a compressor, condenser and evaporator in a closed refrigerant circuit, an electric motor for driving said compressor, said system being provided with means for equalizing refrigerant pressures upon opposite sides of the compressor when the compressor is idle, a current responsive overload control for said electric motor, and means responsive to the temperature of a portion of said refrigerant circuit for controlling the closing of 30 said current responsive control.

15. A refrigerating system including a compressor, a condenser and an evaporator in a closed refrigerant circuit, an electric motor for driving said compressor, an overload control for 35 deenergizing the motor during overload and thereafter energizing said electric motor, latch means for preventing the closing of said overload control, and thermostatic means for unlatching said latch means to release the overload control.

16. A refrigerating system including a compressor, a condenser and an evaporator in a closed refrigerant circuit, an electric motor for driving said compressor, an overload control responsive to current flow through the electric motor for 45 deenergizing the motor during overloads and thereafter energizing said electric motor, latch means for preventing the closing of said overload control, and thermostatic means responsive to the temperature of said electric motor for unlatching said latch means to release the overload control.

17. A refrigerating system including a compressor, a condenser and an evaporator in a closed refrigerant circuit, an electric motor for driving 55 the said compressor, a current overload means responsive to the current supplied to the electric motor for deenergizing the motor during an overload and thereafter energizing said electric motor, and means responsive to a fall in temperature of a portion of said closed refrigerant circuit for controlling the reclosing of said overload control to re-energize the electric motor.

18. A refrigerating system including a compressor, a condenser and an evaporator in a closed refrigerant circuit, an electric motor for driving said compressor, an overload control for deenergizing the motor during overload and thereafter re-energizing said electric motor, latch means for preventing the closing of said overload control, and means for unlatching said latch means to release the overload control.

ROBERT R. CANDOR.
